FREEZING DEVICE

Arthur J. Frei, Sr., Dayton, Ohio, assignor to General Motors Corporation, Detroit, Mich., a corporation of Delaware

Application November 19, 1956, Serial No. 623,089

3 Claims. (Cl. 62—366)

This invention relates to freezing devices of the tray and grid type and particularly to new and useful improvements in the grid structure thereof.

In the art to which this invention pertains it is old to provide a grid structure, removable as a unit from a tray of a freezing device, with a lever or force multiplying mechanism which initially applies a force to the top of an end wall of the tray, to elevate the grid structure relative to the tray for breaking an ice bond between walls of the tray and all ice blocks contained in the grid therein, and to then continue moving the lever or mechanism for moving walls of the grid with respect to one another to release ice blocks from the grid structure. This method of releasing ice blocks from a freezing device caused deformation of the tray end wall and quite frequently such deformation would be so great that the lever became ineffective to perform its designated initial function. Thereafter a freezing device was designed wherein the initial movement of a lever on the grid structure thereof acted initially and directly on the forwardmost transverse grid wall, instead of on a tray wall, and this together with providing a tray with a forward end, in the vicinity of the lever, inclined outwardly from the bottom toward the top of the tray would wedge ice blocks at the front of the freezing device against this inclined tray end to cam or pry the grid and ice blocks bonded thereto upwardly of and loose from the tray. Such a construction overcame the problem of deforming the top of an end wall of a tray but has presented other difficulties. For example force initially applied to the forwardmost end grill wall, to break a bond between the tray and all ice blocks therein, is so great that the interlock between this forwardmost grid wall and an actuating member employed to thereafter move other of the transverse grid walls, particularly in relatively wide freezing devices, would be damaged or broken necessitating replacement of the grid structure. I have found that an interlocking connection of a transverse grid wall directly contacted and moved by a camming surface of a lever on the grid should preferably be made between such transverse wall and two horizontally disposed actuating members, and that both connections must be structurally reinforced to withstand the reactive force of the lever applied to this wall if a grid structure in an ice tray is to be expected to remain infallible in operation for any reasonable period of time.

An object of my invention is to overcome certain difficulties in the production of a grid for use in an ice tray and to provide a durable, easily operated ice tray and grid structure effective for conventionally releasing ice blocks from the tray and for releasing ice blocks from the grid.

Another object of my invention is to provide an improved grid structure for an ice tray of the type wherein all transverse grid walls are normally inclined with respect to the vertical and a lever acts directly on one end transverse grid wall to tilt same and other walls of the grid are tilted in response to movement of this one end

2

wall toward the vertical for releasing all ice blocks from the tray and grid.

A further object of my invention is to provide a plurality of different freezing devices for use in conjunction with a household refrigerator cabinet all of which devices employ identical trays with unlike grid structures therein interchangeable from one to another of the identical trays to meet various demands or desires of a housewife.

10 A still further object of my invention is to provide a unitarily removable grid structure for an ice tray wherein a reactive means or member absorbs force applied directly to one transverse wall of the grid by movement of a lever and transmits this force to a plurality of horizontally disposed spaced apart actuating members simultaneously movable in the same direction to progressively tilt inclined transverse grid walls in succession from one end to the other of the grid toward the vertical whereby the force is divided and applied to the transverse grid walls at spaced apart points therealong, irrespective of whether or not the grid includes one or a number of longitudinal partitions, for preventing an interlocked connection between parts of the grid from being damaged or broken.

15 In carrying out the foregoing objects it is a more specific object of my invention to structurally reinforce a grid for use in ice trays at the critical or most difficult ice bond breaking point in such a manner that substantially inflexible metal walls of the grid can be made from thinner gauge material and parts thereof may be easily and quickly assembled which together enables manufacturing costs of a grid and tray freezing device to be substantially reduced.

20 Further objects and advantages of the present invention will be apparent from the following description, reference being had to the accompanying drawings, wherein a preferred form of the present invention is clearly shown.

In the drawings:

25 Figure 1 is a side view of a tray and grid type freezing device having my improvements incorporated therein;

Figure 2 is a broken top plan view of the device shown in Figure 1 wherein the grid thereof includes a single longitudinal partitioning wall;

30 Figure 3 is a sectional view of my improved freezing device and is taken on the line 3—3 of Figure 2;

Figure 4 is a fragmentary sectional view taken on the line 4—4 of Figure 3 showing a lever pivotally mounted on the single longitudinal grid wall;

35 Figure 5 is a sectional view through the freezing device taken on the line 5—5 of Figure 3 showing an interlock between the longitudinal wall and transverse walls of the grid;

Figure 6 is a broken top plan view similar to Figure 2 of a modified form of freezing device having my invention incorporated therein;

40 Figure 7 is a fragmentary sectional view taken on the line 7—7 of Figure 6 showing a lever pivotally mounted on two longitudinal partitioning walls of the grid structure of the modified device;

Figure 8 is a sectional view through the modified freezing device taken on the line 8—8 of Figure 6;

45 Figure 9 is a broken top plan view similar to Figures 2 and 6 of a still further modified form of freezing device having my invention incorporated therein;

Figure 10 is a fragmentary sectional view taken on the line 10—10 of Figure 9 showing a lever pivotally mounted on the grid structure; and

50 Figure 11 is a sectional view through the freezing device shown in Figure 9 and is taken on the line 11—11 thereof.

55 Referring to the drawings, for illustrating my invention, I show in Figure 1 thereof a freezing device comprising

a tray having a unitary grid structure removably disposed therein. The tray is stamped from sheet metal and is generally represented by the reference numeral 20. Tray 20 includes a bottom wall and opposed upright side and end walls. The tray side and end walls diverge outwardly from their bottoms to their tops and have their upper edge rolled or bent over to provide a rim around the top of the tray. One end of tray 20 has a metal piece 21 welded thereto (see Figure 3) and this metal piece pivotally supports a cam handle 22 which may be of any suitable or conventional construction as is well known in the art. The cam handle 22 serves to break a frost or ice bond between tray 20 and a freezing support upon which the tray may be supported while freezing water therein. The freezing device also comprises a unitary grid structure removably disposed therein for dividing the interior thereof into rows of open-top ice block forming cells or compartments. The grid structure within tray 20 includes a rigid or inflexible metal longitudinal partitioning wall 23 (see Figures 2, 3, 4 and 5) having a plurality of spaced apart notches 24 cut or formed in its bottom edge (see Figures 3 and 5). A plurality of separate rigid or inflexible metal transverse walls 26, the one 27 which may be thicker than the others, are assembled to the longitudinal wall 23 for tilting movement relative thereto. These transverse walls 26 and 27 are each provided with a vertically elongated closed walled key-hole shaped opening 28 through which the longitudinal wall 23 extends (see Figure 5). The opening 28 in walls 26 is of slightly greater height than the height of longitudinal wall 23 so as to permit the longitudinal wall 23 to be extended through the transverse walls during assembly of same thereon. When the walls 26 and 27 come into alignment with the notches 24 longitudinal wall 23 is lowered to position a continuous or web portion 29 on the transverse walls, below the opening 28 (see Figure 5), in the notches 24. Longitudinal wall 23 is also provided with spaced apart laterally bent niches or ears 31 serving as stops for the transverse walls 26 to normally hold them in an acute angled or inclined position with respect to the vertical (see Figures 3 and 5). This normal angled inclination of walls 26 and 27 permits the ice block compartments to be enlarged when the transverse walls are moved toward or into a substantially vertical position as is now well known to those skilled in the art. The inclined transverse grid walls 26 and 27 are provided with horizontally elongated spaced apart closed walled openings 33 (see Figure 5) each of which receives a web portion adjacent an open slot 34, in flat horizontally disposed spaced apart actuating bars or members 36. Slots 34 in bars or members 36 are longitudinally spaced apart and are progressively wider relative to one another from the front to the rear end of the grid structure. After the bars or members 36 are passed through the openings 33 in the transverse grid walls 26 and 27 with the slots 34 registering therewith these members are moved laterally relative to one another to assemble them to the grid structure. A stamped sheet metal lever 40 has legs 41 spaced from and straddling longitudinal wall 23 pivotally secured thereto in back of the one forward transverse wall 27, by a stud or rivet 42 (see Figures 3 and 4). Suitable spacing bushings 43 surround the stud or rivet 42 on each side of wall 23 for holding the lever 40 centralized with respect to the single longitudinal grid wall. Lever 40 is formed to provide a cam surface 44 thereon which normally abuts and is adapted to directly engage the forward transverse grid wall 27 for a purpose to be hereinafter described. Lever 40 is provided with a cut out portion or slot 45 (see Figures 2 and 3) for clearing the longitudinal wall 23 when the lever is swung upwardly about its pivotal mounting. After the lever 40 has been mounted upon the grid a means for tying the ends of bars 36 to one another is secured to the grid. This

means comprises a first metal link element 46 secured to the rear ends of bars 36 by rivets 47 and a second flat horizontally disposed metal link element 48 secured to the front ends of bars 36 by rivets 49. The link 46 is, preferably and especially in the form of my grid disclosed in Figures 1 to 5, bent downwardly (see Figures 2 and 5) so as to prevent rising of wall 23 in the openings 28 of walls 26 and disassembly therefrom. Link 46 could, if desired, on the other hand be flat and riveted to the underside of actuating bars 36. This feature is not required in the modified grid structures herein disclosed and hereinafter described but may be incorporated in the grid shown in Figures 9, 10 and 11 should the central wall thereof tend to become disassembled during relative movement of the grid walls. It is to be noted that the tying link 48 is thicker than link 46 and normally abuts the front surface of transverse wall 27 to thereby absorb the reactive force of cam surface 44 on lever 40 when the lever is operated. The arrangement of link element 48 as described serves to prevent the initial movement of lever 40, which is the most difficult bond breaking portion of operation of the lever, from damaging or breaking interlocked connections between parts of the unitary grid structure.

After water has been frozen in the freezing device shown in Figure 1 into ice blocks in the ice block forming compartments thereof, by the device being subjected to the low temperature within a freezing chamber of a refrigerator cabinet, and it is desired to harvest the ice blocks from the device it is removed from the refrigerator and placed on a flat top support at the kitchen sink or elsewhere as desired. The handle end of lever 40 is now manipulated or raised to cause the cam surface 44 to directly engage and bear against the side of the transverse wall 27 and tilt same forwardly or toward the vertical with a very high mechanical advantage. As lever 40 is continued to be swung upward the brunt of its reactive force applied to the front walls 27 is taken up or absorbed by the link tying means 48 and this force is transmitted evenly and simultaneously to the actuating bars 36. This force, instead of being transmitted to bars 36 solely by one edge of the slots 34, is conjointly transmitted to the actuating bars 36 through rivets 49 and an edge of slots 34 so as to protect the interlock of wall 27 with the bars and prevent damage thereof. The initial tilting of transverse wall 27 cams the two ice blocks at the forward end of the freezing device upwardly along the inclined front end of tray 20 to loosen them from the tray and grid and this camming action also elevates the grid upwardly of tray 20 and loosens all other ice blocks therefrom. In a tray and grid freezing device of the character herein disclosed this initial movement of wall 27 is the most difficult of all other movements of elements of the grid structure and requires the greatest amount of force. In accordance with the objects of the invention my improved grid structure is rendered rugged and of long life by providing means which reinforces the grid and absorbs the reactive force of an operating lever at the point and at a time the greatest force is applied to parts of the structure. Further swinging of lever 40 about its pivotal mounting, after the grid and ice has been broken loose from tray 20, causes the bars 36 to be moved, in response to movement of wall 27, simultaneously in the same direction lengthwise of the grid to progressively pick up the remaining transverse grid walls 26 and tilt them one after the other in succession toward the vertical to break all ice blocks loose from their compartment walls. This is accomplished by the slots 34 in bars 36 being progressively wider than one another in a direction from the front to the rear of the grid structure. This progressive tilting movement of these other or remaining transverse walls 26 does not require the great force needed to tilt the first wall 27. Due to the transverse walls 26 and 27 being normally inclined with respect to the vertical and being tilted toward or into a vertical position enlarges the

ice block forming compartments intermediate the transverse walls and the loosened ice blocks freely fall out of the bottom of the grid. By absorbing the great force initially applied to the grid structure with the reactive force receiving link 48 and transmitting the force to horizontally spaced apart points along the length of the relatively wide transverse grid walls 26 these walls can be safely tilted or moved many times or over and over again without danger of damaging or breaking an interlocking connection thereof with the actuating bar members 36. This is a prescribed requisite peculiar in grids particularly of different construction and all of which are interchangeable with one another in a given size tray of a freezing device or devices of the character herein disclosed. Movements of lever 40 to first tilt cross wall 27 for loosening the two forward ice blocks and all other ice blocks from the tray and for thereafter releasing all of the ice blocks from the grid structure is not illustrated in the drawings but should be obvious to one skilled in the art and to others by reference to prior patented devices of this general nature and particularly to the more detailed description contained in my Patent No. 2,642,726 dated June 23, 1953, entitled Freezing Tray.

In Figures 6, 7 and 8 I show my invention incorporated in a first modified form of freezing device and in which parts of the grid similar or common to those in Figures 1 to 5 of the drawings are indicated by like numerals multiplied by one hundred. In this first modified freezing device a unitary grid structure is removably disposed in the tray 20 and the grid comprises two horizontally spaced apart longitudinal walls 123 which diverge outwardly away from one another at their lower portion so as to permit ice blocks released from the grid walls to freely fall out of the bottom of the grid. In accordance with my invention this grid is provided with the reactive force absorbing link element 148 and the lever 140 thereon has legs 141 each pivotally secured by a rivet or the like 142 to one of the spaced apart opposed upright longitudinal walls 123 (see Figure 7). The two longitudinal partitioning walls of the grid in this modified freezing device divide the interior of tray 20 into three rows of ice block forming compartments. The lever secured to this modified grid is devoid of a central cut out portion or slot since there is no center wall which the lever must clear. The mode of operating or tilting the transverse walls in this first modified illustration of the invention is substantially the same as that described with respect to the showing in Figures 1 to 5 inclusive of the drawings. It is to be understood that the grid in this modified freezing device and the grid in the device shown in Figures 1 to 5 inclusive are interchangeable with one another in the tray 20. Thus a housewife having one of each of the grids so far described may substitute one for the other in a tray 20 to produce larger and fewer ice blocks at one time or smaller and a greater quantity of ice blocks at another time. This provides for the selective freezing and harvesting of different size ice blocks as desired.

In Figures 9, 10 and 11 I show my invention incorporated in a second modified form of freezing device. In this second modified device parts of the grid common or similar to grids shown in Figures 1 to 8 are indicated by like numerals multiplied by two hundred. A unitary grid structure is removably disposed in the tray 20 and the grid of this second modified showing comprises three horizontally spaced apart longitudinal walls 223. The central longitudinal wall is vertically disposed and the two longitudinal walls of each side thereof have their lower portion diverging outwardly or laterally from the center wall to permit ice blocks released from the grid walls to freely fall out of the bottom of the grid structure. In accordance with my invention the grid in this second modified showing is also provided with the reactive force absorbing link element 248. The lever 240 has its legs 241 pivotally secured to the two outer longitudinal walls by rivets or the like 242 (see Figure 10). The three

longitudinal partitioning walls in this second modification divide the interior of tray 20 into four rows of ice block forming compartments. Lever 240 secured to this modified grid structure is provided with the cut out portion 245, similar to the cut out portion 45 of lever 40, so that the web part of lever 240 intermediate its legs 241 will clear the central longitudinal grid wall when the lever is operated to release ice blocks from the freezing device. The manner of operating or tilting the transverse walls in this second modified grid structure is substantially the same as that described with respect to the showing in Figures 1 to 5 inclusive of the drawings. It is to be understood that the tray 20 in all of the illustrated showings of my invention are identical and are of equal size. Thus the grid in this second modified illustration and the grids in the other two freezing devices herein disclosed are interchangeable with one another in a tray 20. In this manner a designated number of trays to be supplied with a household refrigerator cabinet can be provided with different types of grid structures to meet various customer demands.

From the foregoing it should be apparent that my improvement of providing means for absorbing the reactive force of a camming lever on a grid structure can be applied to a wide variety of types of grids for disposition in freezing trays. The combined force reactive absorbing link and actuating bar tying means of the present invention permits of a substantially standardization in grid constructions for ice trays of freezing devices although the grids may include a different number of longitudinal walls for dividing the interior of such trays into various numbers of rows of ice block forming compartments. My method of structurally reinforcing a grid and of absorbing the reactive force of a camming lever applied directly against a partitioning wall thereof prevents deformation of this wall and damage to or breaking of the interlocking connections thereof with other walls or members of the grid structure. The reinforcement of a grid structure as herein disclosed at the critical or most difficult point therein where ice bonds are to be broken renders the grid rugged and of long life.

While the form of embodiment of the invention as herein disclosed constitutes a preferred form, it is to be understood that other forms might be adopted, as may come within the scope of the claims which follow.

What is claimed is as follows:

1. A freezing device comprising in combination, a tray, a unitary grid structure in said tray dividing the interior thereof into ice block compartments and removable therefrom as a unit, said grid structure including a one piece longitudinal partition and a plurality of spaced apart substantially inflexible walls movably secured to said one piece partition and extending transversely thereacross, said transverse walls being normally inclined with respect to the vertical and having two separate spaced apart horizontally elongated closed walled openings therein adjacent the top thereof, a flat horizontally extending actuating bar projecting through each of said separate closed walled openings and having a part thereof interlocked with said transverse walls, said bars extending continuously over the upper portion of said plurality of transverse walls, horizontally disposed flat links secured to ends of said bars beyond and paralleling the endmost transverse walls for tying the two bars together against movement toward one another, a lever on said grid structure pivotally mounted upon said one piece longitudinal partition adjacent an end transverse wall on the side thereof opposite the side traversed by one of said links, said lever having a cam thereon for directly contacting and tilting said end transverse wall toward the vertical, the location of said link being such that the reactive force of said cam against said end transverse wall is absorbed thereby to prevent damaging of the interlock between said end transverse wall and the actuating bars during initial operation of said lever, and continued op-

eration of said lever causing force applied to said end transverse grid wall to be simultaneously transmitted to said bars for moving them in the same direction lengthwise of said grid structure to tilt all other of said plurality of inclined transverse walls toward said end transverse wall into a substantially vertical position.

2. A freezing device comprising in combination, a tray, a unitary grid structure in said tray dividing the interior thereof into ice block compartments and removable therefrom as a unit, said grid structure including a pair of spaced apart one piece longitudinal partitions and a plurality of spaced apart substantially inflexible walls movably secured to said one piece partitions and extending transversely thereacross to provide three rows of ice block compartments, said transverse walls being normally inclined with respect to the vertical and having two separate spaced apart horizontally elongated closed walled openings therein adjacent the top thereof, a flat horizontally extending actuating bar projecting through each of said separate closed walled openings and having a part thereof interlocked with said transverse walls, said bars extending continuously over the upper portion of said plurality of transverse walls, horizontally disposed flat links secured to ends of said bars beyond and paralleling the endmost transverse walls for tying the two bars together against movement toward one another, a lever on said grid structure having a pivotal mounting on each of said pair of one piece longitudinal partitions adjacent an end transverse wall on the side thereof opposite the side traversed by one of said links, said lever having a cam thereon for directly contacting and tilting said end transverse wall toward the vertical, the location of said one link being such that the reactive force of said cam against said end transverse wall is absorbed thereby to prevent damaging of the interlock between said end transverse wall and the actuating bars during initial operation of said lever, and continued operation of said lever causing force applied to said end transverse grid wall to be simultaneously transmitted to said bars for moving them in the same direction lengthwise of said grid structure to tilt all other of said plurality of inclined transverse walls toward said end transverse wall into a substantially vertical position.

3. A freezing device comprising in combination, a tray, a unitary grid structure in said tray dividing the interior thereof into ice block compartments and removable therefrom as a unit, said grid structure including three spaced apart one piece longitudinal partitions and a plurality of spaced apart substantially inflexible walls movably secured to said one piece partitions and extending transversely thereacross to provide four rows of ice block compartments, said transverse walls being normally inclined with respect to the vertical and having two separate spaced apart horizontally elongated closed walled openings therein adjacent the top thereof, a flat horizontally extending actuating bar projecting through each of said separate closed walled openings and having a part thereof interlocked with said transverse walls, said bars extending continuously over the upper portion of said plurality of transverse walls, horizontally disposed flat links secured to ends of said bars beyond and paralleling the endmost transverse walls for tying the two bars together against movement toward one another, a lever on said grid structure having a pivotal mounting on two outermost of said three one piece longitudinal partitions adjacent an end transverse wall on the side thereof opposite the side traversed by one of said links, said lever straddling the center one of said partitions and having a cam thereon for directly contacting and tilting said end transverse wall toward the vertical, the location of said one link being such that the reactive force of said cam against said end transverse wall is absorbed thereby to prevent damaging of the interlock between said end transverse wall and the actuating bars during initial operation of said lever, and continued operation of said lever causing force applied to said end transverse grid wall to be simultaneously transmitted to said bars for moving them in the same direction lengthwise of said grid structure to tilt all other of said plurality of inclined transverse walls toward said end transverse wall into a substantially vertical position.
